William Schmitt INVENTOR

UNITED STATES PATENT OFFICE.

WILLIAM SCHMITT, OF CINCINNATI, OHIO.

SHOW-CASE.

SPECIFICATION forming part of Letters Patent No. 792,732, dated June 20, 1905.

Application filed August 26, 1904. Serial No. 222,284.

To all whom it may concern:

Be it known that I, WILLIAM SCHMITT, a citizen of the United States, and a resident of the city of Cincinnati, in the county of Hamilton and State of Ohio, have invented certain new and useful Improvements in Show-Cases, of which the following is a specification.

My invention relates to a show-case whose top is of glass, whose front and ends are preferably also of glass, and whose bottom and back are of wood, and whose back has a sliding door or a hinged door for enabling the person in charge to open the case and to put articles therein or remove articles therefrom.

15 The material or materials of which the back is made may be varied as preferred.

One of the principal objects of my invention is to provide a unique, handsome, attractive device, economical of manufacture, and which shall well prevent the top glass of the show-case from slipping rearward over the back of the case and shall also prevent this top glass from slipping forward away from the back.

25 The several features of my invention and the various advantages resulting from their use conjointly or otherwise will be apparent from the following description and claims.

In the accompanying drawings, making a part of this specification, similar characters of reference indicate corresponding parts.

Figure 1 is a vertical transverse section of the back of a show-case and of my securing device applied thereto. Fig. 2 is a view in perspective of a portion of the top and of the adjacent portion of the back and of my securing device in position thereon and connected thereto. Fig. 3 is a perspective view of my improved clamp. Fig. 4 is a view of 35 the elastic sleeve which is preferably applied to a lug of the clamp. Fig. 5 is a perspective view of a part of the glass top sufficient to show an opening made therein for the reception of the clamp-lug and the sleeve aforementioned. Fig. 6 is a view in perspective of 45 a portion of the back-strip in which the clamp is fastened and into which the lug of the clamp enters.

I will now proceed to describe my invention 50 in detail.

A indicates the glass top of a show-case. B indicates the vertical front thereof. At the back there will be a top back-piece C immediately under the rear edge part of the glass top A. The door of the case will be in 55 the back and may be hinged thereto or otherwise secured. The preferred mode of uniting the back and the door is by making the latter a sliding one. In such case the upper back-piece and the door will each have guides, 60 which engage each other and allow the door to slide in the direction of the plane of the back and of this upper strip or piece. Whether the projections of these guides are all upon the door or all on the back or rail piece C or 65 part upon each or whether the entire edge of the door or the entire edge of the back-piece C enters a groove in the opposing part is not material to the present invention. A preferred connection to connect the door and the 70 back is illustrated and consists as follows: There are two beads or projecting guides C² C² on the back-piece C, and on the upper edge of the door D are two grooves D² D², which respectively receive the projecting guides 75 C² C². The back-piece C is fixed to the glass top A. The door slides back and forth along the back of the case on the guides D² D². One of the features of my invention consists in providing this back-piece C with an inconspicuous raised rear flange or edge E. This 80 flange or edge may be of a separated piece from the back-piece C and duly secured thereto; but it is preferably made in one with this piece. This piece need not be as 85 high as the top glass is thick. When thus formed, it cannot be seen by a person standing in front of the case, and yet it serves the purpose for which it is put there. It may be beveled at E² in order to avoid a cutting edge 90 being presented to the man behind it and also to improve its appearance. When the glass top A is in position on the back-piece, its rear edge is against this raised edge E. The latter effectually prevents the glass from sliding 95 rearward over the back. Therefore a person leaning against the front of the show-case cannot move this glass top rearward. This raised edge E relieves all the other connections between the glass top and the front and the 100

ends from strain when pressure occurs against the top in a direction toward the back of the case. I also provide in connection a securing-clamp, which is adapted to hold down the 5 glass top on the back C, prevent its being accidentally lifted over the rear edge E, and also securely hold the glass top from being pulled forward. This clamp H has a main or shank portion H² and a bent-down or flanged 10 portion H³ at the rear and at the front a downwardly-extending lug or pin portion H⁴. The shank H² is located on the glass top. The rear flanged portion H³ comes down at the back and is suitably secured to the piece 15 C, preferably by the screws H⁵ H⁶. For obvious reasons I prefer to make a recess C¹ in the rear part of the back-piece to receive the rear flanged portion H³ of the clamp. In the 20 glass top I make a vertical opening A², which receives the lug H⁴. This opening A² is preferably large enough to receive not only the pin H⁴, but also an annular rubber packing or sleeve H⁶, located around the lug H⁴. When 25 the lug H⁴ and its embracing sleeve H⁶ are in position, they closely fit the opening A². I preferably make the lug H⁴ much longer than the thickness of the glass top A and cause the lower part of the lug to be located in an opening C¹ in the back-piece C. Thus located and 30 applied, the clamp is not only secure, but holds the glass top and prevents it from being moved by a pressure against the rear of it or a pull upon it. As is well known in the art, a piece of some soft material, such as felt 35 or rubber, is put between the clamp and the glass and also between the glass and the back-rail. The presence of the edge E prevents any strain being exerted upon the flange H³ in a direction which would tend to draw out 40 the screws H⁵ H⁶ from the back C. Of course the top would for a while be held by the screws without the flange E; but such omission of the flange E is not desirable. The lug H⁴ need not descend into the back C; but 45 it had better do so. When it does, any tendency of the lug H⁴ to ride up and out of the opening A² is prevented. Other advantages are obvious.

When the ends of the case are not of glass, 50 but of other material, as wood, &c., my invention is there applicable and the term "back" herein employed would stand for and include such ends.

A great many slight changes might be made 55 in the general form and arrangement of the parts described without departing from my invention, and hence I do not confine myself to the precise details set forth, but consider myself at liberty to make such slight changes 60 and alterations as fairly fall within the spirit and scope of my invention.

What I claim as new and of my invention, and desire to secure by Letters Patent, is—

1. In a show-case, having a glass top, a back 65 having a raised rear flange E, directly at the

rear of the edge of the glass, the back upholding the glass, and a clamp secured at rear to the back and extending forward over the glass and having an extension or lug located in an opening in the glass, substantially as and for 70 the purposes specified.

2. In a show-case, having a glass top, a back having a raised rear flange E, directly at the rear of the edge of the glass, the back upholding the glass, and a clamp secured at rear to 75 the back and extending forward over the glass and having an extension or lug located in an opening in the glass, and extending down into the back-piece, substantially as and for the purposes specified. 80

3. In a show-case having a glass top, a back-piece having a raised rear flange E at rear of the glass, the glass resting on the back-piece in front of this flange, and a clamp having a rear flange extending down behind the back, 85 and secured thereto, and having a front lug, located in an opening in the glass, substantially as and for the purposes specified.

4. In a show-case having a glass top, a back-piece having a raised rear flange E at rear of 90 the glass, the glass resting on the back-piece in front of this flange, and a clamp having a rear flange extending down behind the back, and secured thereto, and having a front lug located in an opening in the glass, and extending 95 down into the back-piece, substantially as and for the purposes specified.

5. In a show-case, having a glass top, a back-piece having a raised rear flange E, at rear of the glass, the glass resting on the back-piece, 100 in front of this flange, and a clamp having a rear flange extending down behind the back and secured thereto, and having a front lug located in an opening in the glass, and provided with an elastic sleeve, between it and 105 the glass, substantially as and for the purposes specified.

6. In a show-case, having a glass top, a back-piece having a raised rear flange E at rear of the glass, the glass resting on the back-piece 110 in front of this flange, and a clamp having a rear flange extending down behind the back and secured thereto, and having a front lug located in an opening in the glass, and provided with an elastic sleeve, between it and 115 the glass, the lug itself extending down into the back-piece, substantially as and for the purposes specified.

7. In a show-case having a glass top, a back-piece having a raised rear edge, flange E, the glass top supported on the back-piece and located against this raised flange, and a rear recess in this back-piece, a clamp having a rear downwardly-extending back-piece, received 120 into this recess, and secured to the back-piece, the shank of the clamp extending over the glass, and the forward end of this clamp having a downwardly-extending vertical pin, located in an opening in the glass, substantially 125 as and for the purposes specified. 130

8. In a show-case having a glass top, a back-piece having a raised rear edge, flange E, the glass top supported on the back-piece and located against this raised flange, and a rear recess in this back-piece, a clamp having a rear downwardly-extending back-piece, received into this recess, and secured to the back-piece, the shank of the clamp extending over the glass, and the forward end of this clamp having a downwardly-extending vertical pin, located in an opening in the glass, and provided with an elastic sleeve between it and the glass, the lug itself extending down into the back-piece, substantially as and for the purposes specified.

9. In a show-case having a glass top, a back-piece having a raised rear edge, flange E, the glass top supported on the back-piece and located against this raised flange, and a rear recess in this back-piece, a clamp having a rear

downwardly-extending back-piece, received into this recess, and secured to the back-piece, 20 the shank of the clamp extending over the glass, and the forward end of this clamp having a downwardly-extending vertical pin, located in an opening in the glass, and provided with an elastic sleeve between it and the glass, 25 the lug itself extending down into the back-piece, substantially as and for the purposes specified.

In witness whereof I have hereunto set my hand to this specification in the presence of 30 two subscribing witnesses.

WILLIAM SCHMITT.
